UNITED STATES PATENT OFFICE.

CLINTON J. HIXSON, OF SCHENECTADY, NEW YORK, ASSIGNEE TO GENERAL ELECTRIC COMPANY, A CORPORATION OF NEW YORK.

TROLLEY SYSTEM.

1,209,581.

Specification of Letters Patent. Patented Dec. 19, 1916.

Application filed August 6, 1914. Serial No. 855,502.

To all whom it may concern:

Be it known that I, CLINTON J. HIXSON, a citizen of the United States, residing at Schenectady, county of Schenectady, State 5 of New York, have invented certain new and useful Improvements in Trolley Systems, of which the following is a specification.

My invention relates to trolley systems and the like for the transmission of current 10 to vehicles in which flexible contact conductors are suspended at relatively short intervals with the object of minimizing their sag or the tension stress in them, as in the catenary type of construction.

15 Among the advantages obtainable in connection with my invention are high conductivity of the system; continuous contact of current collecting devices with conductors; large contact area and high conductivity or current capacity at the contact; uniform contact pressure; smooth running of collectors on conductors with the absence of shock and arcing; and simplicity, ruggedness, and a cheapness of construction.

20 These and other advantages especially adapt my invention to railways where the traffic is dense and the trains are long, so that very heavy currents must be carried in the trolley system and must be collected at 25 high speeds with the greatest practicable uniformity.

The principles and natures of my invention will appear from the following discussion and from the subsequent description of 30 particular embodiments, while its scope is indicated in my claims.

In the catenary trolley system of my invention, I obtain high conductivity of the trolley system and good contact area and 40 current capacity by employing a plurality of flexible conductors for supplying current to a common collector or contact device, and I obtain smooth running, avoid all hammering or shock, eliminate arcing, 45 and make the contact pressure and the collection of current as uniform as possible by suspending these conductors from the messenger means in recurrent succession, so to speak, instead of in coincidence. I have 50 found that a common messenger can be employed for supporting the conductors, and that in general such an arrangement is preferred to separate messengers for the individual conductors,—both for the sake of 55 simplicity of construction and because it is

difficult to make the tension in separate messengers near enough alike to secure an equality of the pressures between the collector and the several conductors as is necessary for the best results. The employment of a common messenger has also the advantage of reducing the variation in contact pressure as the collector traverses the conductors. 60

In order that each conductor may be entirely free to adjust itself lengthwise irrespective of another, it is best to suspend them independently side by side from the common messenger; and as they are electrically in parallel and at the same potential, I ordinarily prefer to leave them entirely unattached to one another and free to come in contact at their adjacent sides under the influence of gravity and the forces due to their currents and their charged condition rather than to go to the trouble and expense of providing means to keep them apart without interference with their longitudinal adjustment. Indeed, this contact of the conductors throughout their length is if anything an advantage in making the 70 conductivity a maximum on both sides of the trolley collector or contact device in case the latter loses contact with one of the conductors when passing one of its points 75 of suspension. 80

I have herein illustrated and described in detail a catenary trolley system in which two conductors or trolley wires are suspended in alternation, the particular embodiment of my invention shown being the 85 best at present known to me.

While, however, the invention extends to various special combinations and arrangements of parts and specific features and details shown and described, it is not confined 90 thereto, or limited to the use of no more than two conductors, but can be variously carried out and embodied. 95

In the accompanying drawing, Figure 1 is a perspective view of a span of a catenary 100 trolley system constructed in accordance with my invention. Fig. 2 is a fragmentary end-on view of the two trolley wires and a suspension device belonging to each wire. Fig. 3 is a fragmentary side view showing 105 a suspension device for one of the wires. Fig. 4 is a plan view showing the construction at a curve. Fig. 5 is a detail side view of a pull-off device resembling those shown in Fig. 4. 110

As shown in Fig. 1, the flexible messenger 1 (such as a wire or a wire cable) is secured to insulators on the arms 2 carried by the poles or posts 3. The two trolley wires 4 and 5 are freely and independently suspended side by side from the messenger 1 by means of the hangers 6 and 7, the hanger clamps 8 and 9 which form the points of suspension alternating at uniform distances 10 along the wires, so those of one wire are midway between those of the other and the "hard" spots of the one therefore coincide with the "softest" spots of the other. The trolley wires 4 and 5 are shown as slightly 15 separated in Fig. 1, for the sake of clearness of illustration; but it will be understood that in practice they will be in contact with one another, as shown in Fig. 2. The trolley wires 4 and 5 may preferably be of figure 8 20 or other grooved cross-section that will give good hold for the clamps 8 and 9 and at the same time afford such space for the gripping portions of these clamps that they will not interfere unduly with the wires coming in 25 contact. As will be seen from Figs. 2 and 3, the hangers 6 and 7 consist of metal straps bent or looped over the messenger 1 but not attached to it, and the clamp jaw pieces are riveted or otherwise secured to their lower 30 ends and are held together by the bolts 10. It will be understood, of course, that the number, spacing, and length of the hangers 6 and 7 shown are merely illustrative, and may in practice be varied according to the 35 conditions of any particular case. Ordinarily a standard span of 150 feet between messenger supports, a spacing of 15 feet between the hangers of each trolley wire, and a hanger length varying in the span from 8 40 inches to 26 inches will be found good practice. It is simpler and more convenient that each trolley wire should have the same number of hangers in each messenger span, but this is by no means essential.

45 In Fig. 4 I have indicated a suitable mode of construction for a curve,—the curvature shown being of course exaggerated as compared with ordinary practice. Here there is a wire 11 extending from pole to pole, and 50 the messenger 1 and the trolley wires 4 and 5 are "pulled off" from this wire 11 to keep them in suitable positions over the track, there being four pull-off points to a span for the messenger and two for each of the trolley 55 wires. It will be seen that each pull-off point on a trolley wire is close to one on the messenger, so that a common pull-off device 12 may be used for the pull-off connection to the wire 11 (see Figs. 4 and 5). There 60 are therefore four pull-off devices to the span, and as shown they are arranged in two groups of two. Each pull-off device 12 comprises a securing clamp 13 for the messenger 1, and for the trolley wire a clamp 14, a 65 rigid member 15 to one end of which the

clamp is rigidly secured, and an arm 16 rigidly secured to the other end of said member 15. To the clamp 13 and the arm 16 are connected the ends of a wire 17 which is secured to the ends of a member 18 of channel 70 section by means of eyes or clamp hooks 19. The portion of the wire 17 between the clamp hooks 19 forms a sling whose middle is connected to the wire 11, an insulator 20 being interposed in the connection. Different types of insulators are shown in Figs. 4 and 5, but otherwise the pull-off devices in these figures are alike.

It will be observed that the corresponding pull-off points on the two trolley wires do 80 not coincide with one another or with any of the hangers, but are in every case at opposite sides of an intervening hanger for one of the wires, the object of this being to minimize hard spots in the trolley wires and 85 avoid coincidence of those in one wire with those in the other. The pull-off points on the messenger are similarly arranged out of coincidence with those for the trolley wires, in order that the positions of the trolley 90 wires with reference to the messenger may everywhere be as nearly symmetrical as possible with reference to it. In the curve construction of Fig. 4, the two trolley wires hang side by side as nearly as possible in the 95 same horizontal plane, just as in the tangent construction of Fig. 1; but owing to the non-coincidence of their corresponding pull-off points they can not be in contact everywhere, and as shown do not touch at all. It will 100 be understood, of course, that in practice there may be more hangers and pull-off points in a curve span than are shown in Fig. 4, that the pull-offs may be differently arranged, and that the span will ordinarily be 105 longer in proportion to the hanger spacing. For an ordinary two or six degree curve the messenger spans may be 150 feet, the hanger spacing may be 15 feet for each wire, and four pull-off devices arranged as in Fig. 4 110 may be employed. In this case the pull-off devices of each group may be 15 feet apart and the nearest ones of adjacent groups may be 60 feet apart.

A conductor supported at intervals such 115 in comparison with its transverse strength that it is properly to be regarded as flexible will hang between the points of support in a series of more or less flat loops,—no matter how great the tension on it may be,—and at 120 the points of support it will be bent upward more or less abruptly. When a current collector or contact device travels along a single trolley conductor so supported, it will lift the loops more or less, and may even 125 lift the conductor somewhat (though less readily) at the points of support,—if the mode of support permits it, as do the open loop hangers 6 and 7. In spite of this lifting of the trolley conductor, however, when 130

the collector comes to the bend at a point of support it will jump from one loop to the next and will lose contact with the conductor for a short distance as it does so. While 5 the collector is out of contact with the conductor an arc will occur and the current collection will be interfered with, and when the collector strikes the farther loop there will be an objectionable hammer. The like may 10 also occur at a permanent bend in the trolley conductor not at a point of support. The loss of contact will be for a greater distance the higher the speed; and the trouble will also be worse or more serious the greater the 15 voltage and the heavier the current. It will also be worse for direct current than for alternating current. In my type of trolley system comprising two or more trolley conductors with non-coincident support, the 20 trouble just referred to is absent; for when the collector comes to the "hard spot" at a point of support in the wire 4, for example, it will still be in contact with a loop or "soft spot" in the wire 5, and vice versa. 25 The result is that there will be no arc, no shock, and no hammer,—the collector resuming contact and full pressure on the wire 4 gradually and quietly,—all of which means smooth, even, quiet running and is 30 favorable to high running speeds. It will further be seen that there will be less variation in the area, pressure, and current carrying capacity at the contact; and uniformity in these respects favors the handling 35 of high currents satisfactorily almost as much as does the increased normal contact area for a given collector due to the use of two trolley wires instead of one. The best results for high currents will be secured by 40 using a pantograph trolley with a bow contactor or collector having a liberal width of contact surface rather than one with a roller collector.

The multiple conductor catenary construction 45 has important advantages over a direct suspension construction employing a plurality of conductors. In the first place, single conductor catenary construction permits a messenger span and support spacing of, say, 50 150 feet to 300 feet, as compared with a maximum of about 100 feet for single conductor direct suspension construction, and affords various other well-known advantages. In the second place, multiple conductor 55 catenary construction permits the same messenger span and support spacing as single conductor catenary construction, whereas multiple conductor direct suspension construction permits only $\frac{1}{2}$, $\frac{3}{4}$, or $\frac{1}{4}$ the support spacing, according to the number of conductors. For two conductors, there-

fore, the catenary construction requires only $\frac{1}{3}$ to $\frac{1}{6}$ the number of poles required by the other. Again, the catenary construction results in the collector being always in contact 65 with one or the other of the conductors and nearly always in contact with both of them, and also in a much greater uniformity of contact pressure; and the result of all this is that the average contact area and current 70 capacity are much higher.

What I claim as new and desire to secure by Letters Patent of the United States, is:—

1. A catenary trolley system comprising a plurality of horizontally stretched conductors for supplying current to the same contact device suspended from the messenger means in alternation. 75

2. A catenary trolley system comprising a pair of horizontally stretched conductors for 80 supplying current to the same contact device suspended side by side from a common messenger, the points of suspension of each of said conductors alternating with those of the other. 85

3. A catenary trolley system comprising a plurality of horizontally stretched conductors for supplying current to the same contact device suspended side by side and free to come in contact at their adjacent sides but 90 unattached to one another, the successive points of suspension of the respective conductors from the messenger means being themselves arranged in recurrent succession. 95

4. A catenary trolley system comprising a 95 pair of horizontally stretched conductors for supplying current to the same contact device independently suspended side by side from a common messenger and free to come in contact but unattached to one another, the 100 points of suspension of each of said conductors being midway between those of the other. 105

5. The combination with a messenger cable and a pair of trolley conductors, of 105 means for freely suspending each of said conductors from said messenger cable whereby said conductors tend to lie in contact with each other.

6. The combination with a messenger 110 cable and a pair of trolley conductors, of a plurality of staggered hangers of equal length for alternately pivotally suspending each of said conductors from said messenger cable whereby said conductors tend to lie in 115 contact with each other.

In witness whereof, I have hereunto set my hand this 5th day of August, 1914.

CLINTON J. HIXSON.
